INSERT BAG STIFFENERS

Amund S. Roper, Buffalo, N. Y., assignor to Bemis Bros. Bag Company, Minneapolis, Minn., a corporation of Missouri

Application March 13, 1953, Serial No. 342,102

8 Claims. (Cl. 229—55)

The present invention relates to improvements in the construction of containers made of paper, light cardboard, cloth and other flexible materials that are used for the packaging and display of bulk material, such as flour, cereal, sugar, soap powders and other like commodities, and more particularly to improvements in stiffening inserts for said containers.

The present invention relates to improvements in foldable merchandise containers, which are made and shipped in a flat condition and are then filled and closed at the plant, factory or mill producing the commodity to be sold. The containers, more usually called "bags," are of rectangular parallelepipedon shape and have a pair of major walls (front and back), a pair of minor walls (sides), a bottom and a top closure. Such containers or "bags" are economical to make and use since they can be shipped and stored in a small space. They may be constructed in accordance with the "flat-fold" or "in-tucked" principle. The bags are shipped in collapsed (flat or intucked) form from the bag manufacturer to the commodity producer or packager, and he stores these bags in collapsed form until they are needed. At that time the commodity producer or packager will "set up" (open) the containers, fill them with merchandise, close them and ship them on for ultimate sale to the consumer.

Bags of this type are used for bulk granular solids, such as sugar, salt, rice, barley, breakfast foods, etc. These commodities, by their nature, flow in a manner much like a liquid. When a bag of this commonly accepted type is filled, the bulk granular solid exerts an internal pressure which causes the containers to become somewhat rounded at the corners and edges. This is undesirable because it uses more space for transporting in boxes and more especially because of the poor display features of such containers when placed on the merchant's shelf for ultimate display and sale to the consumer. Thus, a somewhat rounded-off bag does not present neat, wide, flat front and back surfaces for the display of trademarks, manufacturer's name, etc.

It is desirable for economy to use containers which fold flat before filling, but for merchandising purposes the container should retain substantially the form of a rectangular parallelepipedon after filling, so as to present flat or nearly flat walls as well as neat edges and corners. However, this objective has not been possible to attain in practice.

In the design of bags of this type, the greater the difference in the areas of the various faces (front, back, sides, top and bottom), the greater will be the tendency of the bag body to bulge outwardly on the area of the faces, and consequently assume a more or less rounded shape or form. In other words, a bag having a theoretical bag shape wherein the width of the front and back, as compared with the width of the sides, differ greatly, will have a greater tendency to bulge and assume a rounded appearance. Therefore, the foldable bag designer has had to keep the dimensions of the bag such that the width

2

of the front and back panels does not greatly exceed the width of the sides, especially for freely flowing materials, such as coffee, rice and beans. Accordingly, there has been practical limits beyond which the bag designer could not usually go, and as a result the ratio of widths (i. e. front and back to sides) has generally been held below 2 to 1 and even then the aforesaid bulging and rounding has to some extent had to be tolerated as a problem heretofore incapable of economic solution.

From the merchandising standpoint in competitive markets it is desirable to have as much space as possible on the front and back panels of the bag so as to allow prominent display of trademarks, etc., but provision of much space on these faces of the bag has been made impossible in packaged goods except by the use of rigid boxes made of strong paperboard having inherent stiffnesses sufficient to withstand the aforesaid distorting "pressure" of the commodity within the package. However, use of such rigid packages is limited, since when empty they cannot be shipped economically after being "set up" because of the large space they occupy, and hence are usually fabricated by large and expensive machinery at the place where they are to be filled with the commodity. In addition, the cost of rigid cardboard of quality sufficient to make the exterior of a bag generally exceeds the cost of paper. Smaller mills cannot afford machinery to make boxes at the place of filling.

In addition to the problems of bulging as aforesaid, there is the problem of leakage and spillage when a flexible walled container becomes damaged. Since these bags are necessarily made of material which is by its nature, pliable or flexible, the body of the bag is subject to rupture and in case of a rupture, all or a portion of the contents of the container may be spilled and lost.

It is an object of the present invention to provide an improved flexible walled container which is economical to make and ship, capable of being folded flat when empty, constructed so as to resist bulging and rounding, and more nearly resembles a box in appearance when it is filled and closed.

It is a further object of the invention to provide an improved flexible walled container capable of being folded flat for storage and yet capable of being set up into a relatively flat rectangular package presenting flat walls with neat edges and corners.

It is a further object of the invention to provide an improved bag structure having reinforcement capable of maintaining selected walls of the filled bag in flat neat condition.

It is a further object of the invention to provide an improved bag structure capable of being set up and filled to provide a package of substantially rectangular parallelepipedon configuration wherein the front and back are relatively much greater in width as compared to the sides than has heretofore been possible in such bag structures.

It is a further object of the invention to provide a flexible walled bag structure wherein reinforcements are provided throughout substantially the entire extent of the walls of the bag when filled.

It is a further object of this invention to provide foldable flexible walled bags having a stiffening insert designed to reinforce the entire surface of the front, back and side walls as well as the bottom and top closure portion of the bags.

Other and further objects of the invention are those inherent and apparent in the apparatus herein illustrated, described and claimed.

The invention is illustrated with reference to the drawings in which corresponding numerals refer to the same parts and in which:

Figure 1 is a plan view of a stiffening insert blank,

showing in dotted lines, the scored lines upon which the blank will subsequently be folded;

Figure 2 is a plan view of the insert blank as shown in Figure 1, wherein the outer bottom tabs have been folded inwardly along score lines;

Figure 3 is a plan view of the blank as shown in Figures 1 and 2, but wherein the bottom face portion has been folded inwardly;

Figure 4 is a side elevational view of the folded blank, shown in Figure 3;

Figure 5 is a plan view of the insert blank after being folded inwardly about the bottom portion;

Figure 6 is a side elevation of the stiffening insert blank as folded in Figure 5 taken in the direction of arrows 6-6;

Figure 7 is a sectional view through a paper bag showing the stiffening insert blank partially inserted therein;

Figure 8 is a perspective view, partially broken away, showing the stiffening insert fully inserted within the flexible container;

Figure 9 is a horizontal sectional view taken along the line and in the direction of the arrows 8-8 of Figure 8;

Figure 10 is a plan view of a slightly modified form of stiffener insert, blanked, and showing in dotted lines the scores upon which the blank will be folded;

Figure 11 is a plan view, partially broken away, of the stiffener insert of Figure 10, wherein it has been folded along a median line;

Figure 12 is a plan view of the stiffening element folded as in Figure 11 and having some of the edge portions of the blank taped together;

Figure 13 is a side elevational view of the stiffening element shown in Figure 12 showing the bottom of the blank in a partially folded condition;

Figure 14 is a side elevational view similar to Figure 13 but wherein the bottom portion of the stiffener has been folded further;

Figure 15 is a plan view of the blank having its bottom portion folded as in Figure 14;

Figure 16 is a fragmentary plan view similar to Figure 15 wherein portions of the bottom tab have been folded inwardly;

Figure 17 is a plan view of the blank of Figures 10-15 having its bottom portion folded in the final desired manner;

Figure 18 is a sectional view taken along the lines and in the direction of the arrows 18-18 of Figure 17;

Figure 19 is a perspective view of the stiffening insert shown partially inserted into the flexible walled container;

Figure 20 is a perspective view partially broken away of a flexible walled container having stiffening insert therein;

Figure 21 is a horizontal sectional view of the container and insert therein taken along the lines and in the direction of the arrows 21-21 of Figure 20;

Figure 22 is a perspective view of an additional modification of the present invention;

Figure 23 is a fragmentary plan view of an additional modification of the present invention showing a portion of the bottom section of the blank;

Figure 24 is a fragmentary plan view of the modification shown in Figure 23, wherein a line of adhesive tape has been attached along an edge thereof; and

Figure 25 is a perspective view of the modification as shown in Figure 23 when inserted within a flexible container.

In Figures 1-9 there is illustrated the preferred modification of the present invention, Figures 8 and 9 illustrating the device as mounted within a flexible walled container.

According to this illustrative embodiment of the invention, Figure 1 shows a blank generally designated 10 having the major portions 11, 12, 13, 12A and 11A. The

brackets 11 and 11A include the top portions of the insert, 12 and 12A include the body portions and 13 includes the bottom portion of the insert.

The bottom portion 13 is comprised of a bottom face portion 15 and gusset portions 16, 17, 18 and 19. The body portion 12 includes a face portion 21 lying between the score lines 38 and 39, straddled by a pair of side wall portions 22 and 23. The top portion 11 includes a pair of identical folding tabular portions 25 and 26 which straddle a tongue portion 27. Below the bottom portion 13 is another body portion 12A and a top portion 11A. These body and top portions are in every way identical to the corresponding portions heretofore explained.

Attention is now directed to Figure 2 where the first step in forming the insert 10 is illustrated. The tabs 16, 17, 18 and 19 are folded upwardly and inwardly along the score lines 16A, 17A, 18A and 19A until the tabular portions are in flush contact with the face portion 15 of the bottom. Next the bottom is folded along a median scored line 29, the body portions 12 and 12A are brought close together, as shown in Figure 3, folding along the score lines 30 and 31.

Figure 4 is a side view of the blank 10 folded as in Figure 3. The body portions 12 and 12A are then folded so that they will be in superimposed relationship and have the already folded bottom portion 13 therebetween. Figures 5 and 6 illustrate the blank where it has been folded thus, thereby forming the insert of the instant device.

The insert is now ready to be inserted in a flexible bag, and a bag of the "flat-fold" variety is used for this purpose. In Figure 7, the insert, as heretofore described and prepared, is shown as it is being inserted within a bag 34, and Figure 8 illustrates the insert 10 after insertion in the bag and after the bag has been "set up."

It will be understood that the inner dimensions of the bag will be substantially commensurate with the outer dimensions of the corresponding dimensions of the insert panel.

In "setting up" the bag, the end portions 22, 23, 22A and 23A of the insert and the bottom gusset portions 35 and 36 are folded inwardly at right angles along the score lines 38 and 39. These gusset portions fit into the opening formed by the notches 40, 41, 42 and 43, which are cut diagonally into the side faces toward the bottom portion 13 when the bag is opened and "set up." (These notches 40, 41, 42 and 43 also serve to provide an opening into which the bottom may be infolded when the bag and insert are folded in a flat condition.) Thus, there is formed substantially a rectangular parallelepiped open at the top, as shown in Figure 8.

The front face portion 21 of the blank therefore is bounded by the score lines 37, 38, 30 and 39, and the dimensions of this face substantially correspond to the dimensions of the front or back major walls of the flexible walled container. Likewise, the end walls are formed from the combination of the end portions 22 and 22A, as well as the combination of the end portions 23 and 23A. The bottom wall of the insert when formed from the blank 10 is bounded by the scored lines 30, 38, 31, 39. The top wall of the insert is formed by the combination of the tabs 25, 25A, 26, and 26A, and the tongues 27 and 27A, all of which lie outwardly from the score lines 37 and 37A.

The bag and insert as shown in Figure 8 are ready for filling. The bag is filled with bulk material to the line 37B, and in order to close it, the tabs 25, 26, 25A and 26A are folded downwardly and inwardly at right angles along the score lines 37 and 37A. The tongues 27 and 27A are then folded inwardly and downwardly along the score lines 37 and 37A, one over the other, thus forming a closure for the body of the container. The portions of the bag 34 lying above the line 35 are folded

inwardly and sealed in order to form the outer top closure. The filled container unit is then complete and ready for use in commerce.

Attention is now directed to Figures 10-20 wherein a slight modification of the present invention is illustrated. In appearance this modification is substantially similar to the device previously disclosed with the exception of the notches 40, 41, 42 and 43 which are cut into the side portions of the previously described device. Figure 10 shows a blank 45 having top portions 46 and 46A, body portion 47 and 47A and a bottom portion 48.

The top portions 46 and 46A comprise central tongue portions 50 and 50A, respectively, each of which are straddled by a pair of tubular portions 51, 52 and 51A and 52A, respectively. The body portion 47 and 47A are each comprised of a face portion 54 and 54A, respectively, as well as side wall portions 55, 56, and 55A and 56A. The bottom portion 48 comprises a face portion 58 and gussets 59, 60, 61 and 62.

Extending from the edge surface of the bottom portion 48 and from the adjacent edge surface of the body portions 47 and 47A are the lateral projections 64-64. These are present in order that the insert when formed from the blank will more closely conform with the form of the container.

Attention is now directed to Figure 11 where the first step in forming an insert from the blank 45 is illustrated. The blank is folded along the scored line 65, which is the median line of the blank 45 and the two similar portions of the blank are then in superimposed position.

The next step in the assembly includes securing together of a portion of the superimposed edge surfaces of the blank, as shown in Figure 12. An adhesive backed tape 66 is applied to the other lateral edge surfaces of the superimposed body and top portions of the blank 45.

Figure 13 illustrates the folding and forming of the bottom of the insert. From the flat position, the lower median portion of the blank is raised and pushed inwardly, thus causing relatively sharp bends on the score lines 69 and 70, and a less sharp bend at 71. This bending movement is continued until the blank assumes the position as illustrated in Figures 14 and 15. Next, the gusset sections 59-59A, 60-60A, 61-61A and 62-62A are folded inwardly and over, for example, as is clearly illustrated in Figure 16. The bottom is then tucked inwardly along the median line 65 between the scored lines 69 and 70, as is shown in Figures 17 and 18.

The insert is then ready to be placed within the bag 71. The bag 71 is of the "flat-fold" type and when "set up" appears as shown in Figure 20. The "setting up" as well as filling and closing of this bag is accomplished in the same manner as that previously disclosed in connection with the prior insert.

As previously disclosed, the blank 10 was assembled and formed into an insert without the aid of an adhesive backed tape. However, as disclosed in the assembly of the blank 45, an adhesive backed tape was used to assist the assembly thereof. As a modification of the assembly of the same type as blank 10, adhesive backed tape may be used in conjunction therewith. An insert formed and assembled from a blank identical to blank 10 is shown in Figure 22.

Attention is now directed to Figures 23-25 for a discussion of an additional modification of the present invention.

A portion of a blank 75 is illustrated in Figure 23. This partial view is taken chiefly from the bottom portion section of the blank 75. The chief differences in this blank and the previously discussed blank lies in the design of the bottom portion 76. It may also be noted here that the blank 75, as shown herein, does not have a top portion attached thereto, but it is to be understood that the top may be included, if desired, as in the previously discussed blanks.

The blank 75 comprises face portions 78 and 78A

having end wall segments 79, 80, 79A and 80A. These end wall segments function the same way as do those of the previously discussed blanks. The bottom portion 76 has a face portion 81 and semi-elliptical shaped tabs 82-82.

In assembly of the blank 75 the device is folded along the median line 84 on the bottom 76, so that the two corresponding portions are in superimposed position. A pair of strips of adhesive backed tape 85-85 is then applied to portions of the outer edge surface of the end wall segments as shown in Figure 24. The semi-elliptical tabs 82-82 are then folded inwardly along the score line 86, after which the bottom face portion 81 is folded inwardly from the position shown in Figure 24, the final step being folding the gusset portions 87-87 inwardly of the position shown in Figure 24.

The insert is then ready to be placed within a bag, and this again is accomplished in the manner disclosed heretofore with respect to the other blanks. Of course, the dimensions of the faces of the insert are selected so that they substantially correspond to those of the bag into which it is inserted.

It may be noted that the face portion 78 extends outwardly at its upper end beyond the end wall as formed by the segments 88. The reason for this design lies in the fact that stresses put on the outer bag body at the point where the end wall of the insert terminates will be lessened. The rounded corners as at 89 are likewise designed to distribute stress over a greater proportion of the outer bag body than would be accomplished by having a sharp corner.

Various modifications of the present invention have been illustrated both with and without a top closure portion. It will be understood, however, that it is possible to utilize the top closure portion with any or all of the disclosed inserts, and it is also possible to use the same without the use of a top closure portion.

As many apparently widely different embodiments of this invention may be made without departing from the spirit and scope thereof, it is to be understood that I do not limit myself to the specific embodiments disclosed herein.

What I claim is:

1. A tubular bag of flexible material adapted to be folded to a flat condition, said bag having a pair of major walls, a pair of minor walls, a bottom, and top closure portions adapted to be folded over each other to form a top when said bag is filled and closed, said bag body, when closed, forming a theoretical container shape substantially in the form of a rectangular parallelepipedon, a reinforcing insert of relatively stiff material within said bag, said insert having a pair of major walls, a pair of minor walls, and a bottom wall portion, said faces registering, respectively, with and being substantially geometrically commensurate with the inner surface of the corresponding walls of the bag when said insert is within said bag body, a pair of gusset portions extending from opposite edges of said bottom wall, said minor walls being notched adjacent the bottom thereof to receive said gusset portions when said bag and insert are opened, and to receive said bottom in an infolded manner when folded in a flat condition.

2. The structure of claim 1 further characterized in that each of said minor walls comprises two portions joined along a vertical median line.

3. The structure of claim 1 further characterized in that said gusset portions each comprise triangular tabular portions of double ply.

4. A tubular bag of flexible material adapted to be folded to a flat condition, said bag having a pair of major walls, a pair of minor walls, a bottom, and top closure portions adapted to be folded over each other to form a top when said bag is filled and closed, said bag body, when closed, forming a theoretical container shape substantially in the form of a rectangular parallelepipedon,

a reinforcing insert of relatively stiff material within said bag, said insert having a pair of major walls, a pair of minor walls, and a bottom wall portion, said faces registering, respectively, with and being substantially geometrically commensurate with the inner surface of the corresponding walls of the bag when said insert is within said bag body, said bottom having extending therefrom a semi-elliptical portion adapted to be folded normal to the bottom when the bag is "set up," and parallel thereto when folded flat, diagonally foldable gussets at the bottom of said minor walls, said gussets adapted to be foldable inwardly of and normal to the plane of said minor wall portion when the bag is folded flat and parallel thereto when said bag is "set up."

5. The subcombination of a bag reinforcing insert of relatively stiff material, said insert having a pair of major walls, a pair of minor walls, and a bottom wall, said bottom having extending therefrom a semi-elliptical portion adapted to be folded normal to the bottom when the bag is "set up," and parallel thereto when folded flat, diagonally foldable gussets at the bottom of said minor walls, said gussets adapted to be foldable inwardly of and normal to the plane of said minor wall portion when the bag is folded flat and parallel thereto when said bag is "set up."

6. The structure of claim 5 further characterized in that each of said minor walls comprises two portions joined along a vertical median line.

7. A tubular bag of flexible material adapted to be folded to a flat condition, said bag having a pair of major walls, a pair of minor walls, a bottom, and top closure portions adapted to be folded over each other to form a top when said bag is filled and closed, said bag body,

when closed, forming a theoretical container shape substantially in the form of a rectangular parallelepipedon, a reinforcing insert of relatively stiff material within said bag, said insert having a pair of major walls, a pair of minor walls, and a bottom wall portion, said faces registering, respectively, with and being substantially geometrically commensurate with the inner surface of the corresponding walls of the bag when said insert is within said bag body, a pair of gusset portions extending from opposite edges of said bottom wall, and each comprising a triangular member joined at its base to said bottom wall, said minor walls each having a fold line corresponding to the sides of a respective triangular member and a pair of co-extensive triangular pieces joining said fold line to each of said sides of said respective triangular member.

8. The structure of claim 7 further characterized in that each of said minor walls comprises two portions joined along a vertical median line.
